UNITED STATES PATENT OFFICE.

EUGENE PETERSON, OF NEW YORK, N. Y., ASSIGNOR TO WESTERN ELECTRIC COMPANY,
INCORPORATED, OF NEW YORK, N. Y., A CORPORATION OF NEW YORK.

MODULATION.

Application filed December 29, 1923. Serial No. 683,301.

This invention relates to modulation, and particularly to modulation of higher order than the second, or other methods of modulation producing side bands of similar frequency characteristics and its application in carrier wave communication systems.

Modulation, as used herein, relates broadly to that class of phenomena which accompanies or, in fact, is produced by distortion of electric waves, and especially to phenomena which occur when two waves, one the so-called carrier wave and the other the modulating wave, are jointly impressed on a distorting instrumentality.

It is well known that modulation of this kind yields side frequencies made up of various combinations involving the frequencies of the impressed waves. When one of the waves, either the modulating or carrier wave

20 consists of a band of frequencies the side frequencies likewise assume the form of bands.

The number, amplitude, and frequency characteristics of these side bands is a function of the kind and extent of the distortion as measured, for example, by the equation of the characteristic curve which expresses the relation between the amplitude of the input and output quantities.

In the present systems, use is made of the 30 "square" characteristic of this curve, that is, the characteristic which makes the equation of the curve approach the form $y = kx^2$, in which x and y are respectively the amplitudes of the input and output quantities.

35 Other terms having other powers of x may, to some extent, be present. Those in other even powers of x will contribute to the effect secured by the square term as will be explained later. On account of this "square"

40 characteristic, modulation yields side band components having frequencies equal respectively to the sum and difference of the frequencies of the modulating and carrier waves. These side bands with or without

45 some of the original carrier constitute a modulated carrier wave from which the modulating component may be reproduced at a receiving station by a similar distortion.

The terms besides the "square" term, if 50 present, in addition to contributing to the effect of the "square" term, as above, produce other side bands in which harmonics of the carrier or modulating frequencies, or both, instead of the fundamental frequencies, 55 occur. These various combination frequency

components or side bands are distinguished from each other by the number of times the carrier and modulating frequencies, taken together, occur. This distinction is made use of in defining the order of modulation which produces these components. For example, second order modulation produces side bands of the usual kind, in which the carrier and modulating frequencies each occurs once, third order of modulation results in side bands in which the first even harmonic of either the carrier or modulating frequency occurs, etc.

An object of the invention is to provide modulating means which are simpler, more 70 efficient, rugged, and less expensive, than modulating means heretofore invented.

Another object is the practical utilization of third, and higher order, modulation, or of modulation side bands of similar frequency characteristics.

A still further object is to produce a suppressed carrier, signal modulated wave, without the use of balanced circuits.

Another object is to effect odd order modulation to the substantial exclusion of even order modulation.

A still further object is to provide improved means for generating third order side bands of relatively great amplitude.

Additional objects of the invention are: to achieve harmonic multiplex communication using a single source of carrier waves, prime or secondary, for all of the channels; to provide an improved system of two-way 90 communication having different carrier frequencies and a single carrier source; the production of odd harmonics for use as carrier frequencies; and to provide an improved system of secret communication.

The various means suggested for producing pronounced higher order modulation side bands each involves means for producing, and operating over, a characteristic curve which has one or more pronounced 100 bends. In the particular case in which it is desired that odd order modulation side bands should be obtained to the exclusion of the even order side bands, the curve should have two symmetrical bends in relatively 105 opposite directions, that is the curve should have opposite symmetry about each of the axes of coordinates through a point on the curve and the operation should occur equally over the curve in both directions 110

about the point. If the operation does not occur about the point of symmetry or if the curve lacks symmetry of this kind, even order side bands will be present. Similarly, even order side bands can be obtained, to the exclusion of odd order side bands by operating over a curve which has opposite symmetry with respect to only one of the axes, as, for example, a parabola. These two forms of symmetry are often, and more simply, designated respectively "symmetry about a point" and "symmetry about a line". In general, for either case, the acuteness of the bends indicates proportionally the order of the more pronounced side bands. It does not necessarily indicate anything as to the number of kinds of modulation of different orders that may be present.

It has been found that a closed magnetic core designed for saturation at small magnetizing currents makes possible the production of pronounced odd order side bands to the substantial exclusion of even order side bands. The modulating and carrier currents are used to variably magnetize the core by impressing them on a common coil, or on different coils, mounted on the core. On account of its unusual magnetic qualities the alloy known as "permalloy" has been found to be ideal for the purpose. This alloy is described in a paper by Arnold and Elmen in the Journal of the Franklin Institute for May, 1923.

A similar effect can be obtained, using electron discharge devices, by inserting a high impedance in series with the grid of a conventional three-electrode discharge modulator. The impedance may be a conductive element of the usual kind or a half-wave rectifier. An abrupt bend in the normal space current grid voltage characteristic curve occurs at the point corresponding to the instant when an increasing impressed alternating current voltage passes through zero value, on account of the relatively large voltage drop that occurs in the series impedance at and subsequent to this instant of time. According to the criterion mentioned above, pronounced even order modulation effects can be obtained from a tube having this characteristic. By operating beyond the foot of the normal characteristic, a second abrupt bend in the opposite direction can be made to occur at this point. Pronounced odd order modulation effects can be secured, as has been pointed out, from a modulator having this characteristic.

Somewhat similar effects can be obtained by the use of an arrangement consisting of two such combinations of modulator and rectifier connected in opposition. This arrangement has the advantages that it more effectively utilizes both half waves of the impressed alternating wave and that it results in a more perfect symmetry than can

be secured by the use of one such combination.

The symmetry obtained by using a push-pull combination of two three-electrode modulator tubes, somewhat similar to the well known balanced modulator circuit, may be utilized to produce odd order modulation side bands to the exclusion of even order side bands, or vice versa, with accompanying suppression of the impressed carrier or certain of its derivatives. The use of this general arrangement or another arrangement including a single tube circuit having the requisite symmetry of characteristic with an output filter, makes possible the production of higher order side bands with complete suppression of the components which could otherwise be used in combination with the received side bands at a distant station, by even or odd order demodulation, to reproduce the signal. In particular a single tube or a magnetic core modulator when arranged to have symmetry about a point suppresses, for example, the double carrier. Since the fundamental carrier may easily be separated by a filter from the resultant third order side bands the use of a modulator of this type can accomplish a result similar to that accomplished by a balanced arrangement of tubes in second order modulation with carrier suppression.

Systems using higher order modulation or other methods of modulation producing side bands of similar frequency characteristics may use the same order of demodulation if the original carrier is transmitted or locally introduced at the receiver. If a harmonic of the carrier is transmitted or locally introduced the order of modulation and demodulation may be different.

If a lower third order side band or a side band of similar frequency characteristics produced by other orders of modulation and the impressed carrier are transmitted, and the double frequency carrier is suppressed, and if the frequency of the carrier is chosen close to the upper limit of the impressed signal band, secret telephone communication is possible since an interceptor provided only with second order demodulation circuits will hear inverted speech. A receiver provided with a third order demodulator which suppresses the even order side bands would be able to reproduce speech to the exclusion of the inverted speech.

Harmonic multiplex communication is made possible by using one carrier source and different orders of modulation for the several channels.

Two-way communication using different frequencies for the two directions but a single carrier source may be similarly achieved. These two principles may be jointly applied in a multiplex two-way harmonic system of communication.

The invention both as to its theoretical principles and its practical embodiments will be better understood by reference to the following detailed description, together with the accompanying drawing, in which,

Fig. 1 is a graphical diagram illustrating certain theoretical principles of the invention.

Fig. 2 discloses a circuit for obtaining odd order modulation with complete carrier suppression.

Fig. 3 discloses a circuit for obtaining pronounced odd order modulation side bands with elimination of even order side bands and even power carrier harmonics, or conversely for obtaining pronounced even order modulation side bands with elimination of odd order side bands and odd power harmonics.

Figs. 4, 5, 6 and 6^a are graphical diagrams illustrating certain theoretical principles of the operation of the systems of Figs. 3 and 7.

Fig. 7 discloses a modulator which may be used alternatively to that of Fig. 3, to accomplish substantially the same result.

Fig. 8 discloses a typical one-way carrier current system employing higher order modulation and also one form of magnetic core modulator.

Fig. 9 illustrates graphically certain theoretical principles involved in the operation of the modulator of Fig. 8.

Figs. 10, 11, 12, 13 and 14 disclose other forms of magnetic core modulator, and

Figs. 15 and 16 disclose systems alternative to that of Fig. 8 for utilizing the principle of modulation of higher order than the second or of methods of modulation producing side bands of similar frequency characteristics.

In order to aid in an understanding of the general nature of the invention and to elucidate the characteristic qualities of the various specific systems in which it may be embodied and to properly appraise its advantages as applied therein, the following mathematical analysis of modulation, especially higher order modulation, is given.

If currents of different frequencies p and q are fed into a distorting (modulating) device, there results a complex current in which the frequencies have the general form $mp \pm nq$, in which m and n may have any or all integral values, or zero values, and in which the symbol $\pm$ indicates that the sum, the difference, or both the sum and difference, of the two quantities may be present. This statement will be proved later when the complete equation expressing the modulated current is derived.

When either of the coefficients m or n has zero value, the current defined by this expression is a direct current if the other coefficient is zero. If the other coefficient is

not zero, the current will have components the frequency of which is p or q , as the case may be, or various harmonics thereof. When neither of the coefficients has zero value there are obtained combination frequency components, that is, side bands. The order of modulation is conveniently given as the sum of m and n . When both m and n are unity we have the familiar case of second order modulation in which the side frequencies are $p \pm q$. Third order modulation may be correspondingly represented by $2p \pm q$ or $p \pm 2q$. There are accordingly four possible third order side frequencies. If r is a number expressing the order of modulation (that is, a number which is the sum of two numbers) it is evident that there are $r-1$ combinations of different numbers which add up to equal r , so that, considering both the sum and difference frequencies, there may be a maximum of $2(r-1)$ different side frequencies for each of the respective orders of modulation.

In what follows, it will be assumed that q represents a band of frequencies as, for example, a voice current (the so-called modulating current) and that p represents a fixed carrier frequency having a value greater than the greatest value of q . The expression "side band" will accordingly be used instead of "side frequency." Also, only the side bands in which q occurs once, that is, those having frequencies $p \pm q$, $2p \pm q$, $3p \pm q$, etc., will be considered, since obviously only by the transmission of side bands of this type can the modulated component be reproduced at the receiver by modulating such side bands with a wave having the frequency of the unmodulated carrier or a harmonic thereof.

In order to prove that various multiple order side bands occur and to determine the extent to which they occur, an extension of the method of analysis used in U. S. patent to Carson, Serial No. 1,449,382, issued March 27, 1923, will be used.

According to that method a statement of the current (or potential) resulting from modulation is obtained by substituting in the general equation of the type $y = ax + bx^2 + cx^3$ values of simultaneously impressed currents (or potentials). Suppose that the input currents are $P \cos p_1 t$ and $Q \cos q_1 t$, in which p_1 and q_1 equal respectively $2\pi p$ and $2\pi q$, so that x equals $P \cos p_1 t + Q \cos q_1 t$. (No material change would result if an initial phase angle between the two impressed waves were assumed.)

This value of x should be substituted in the general equation. The first term $a x$ yields merely amplified waves of the impressed frequencies p and q . The term $b x^2$ yields waves of frequencies $2p$, $2q$, and $p \pm q$, as is well known. The second order side bands $p \pm q$ result from the trigono-

metric expansion of the product $bPQ \cos p_1 t \cos q_1 t$. The harmonic frequencies $2p$ and $2q$ result from trigonometric expansions of, respectively, $bP^2 \cos^2 p_1 t$ and $bQ^2 \cos^2 q_1 t$.

If each of the remaining terms of the general equation are algebraically expanded by the binomial theorem, it will be found that the expanded equation comprises terms in 10 powers of $\cos p_1 t$ and $\cos q_1 t$, and terms which contain the product $\cos p_1 t \cos q_1 t$ as a factor. The first two obviously yield waves whose frequencies are, respectively, harmonics of p and q . The last obviously 15 yields combination frequency waves, that is, side bands.

Considering these terms which produce combination frequency waves, it will be found that alternate terms, beginning with 20 the second, in the expansion of even power terms of the general equation are of this type and are further characterized in that the exponents of $\cos p_1 t$ and $\cos q_1 t$ are each odd. These terms in their regular order, up 25 to and including the expansion of the sixth power term of the general equation, are as follows, only those coefficients which are necessary in this discussion being retained:

$$\begin{aligned} 30 & \quad PQ \cos p_1 t \cos q_1 t \\ & \quad P^3 Q \cos^3 p_1 t \cos q_1 t \\ & \quad PQ^3 \cos p_1 t \cos^3 q_1 t \\ & \quad P^5 Q \cos^5 p_1 t \cos q_1 t \\ & \quad P^8 Q^3 \cos^3 p_1 t \cos^3 q_1 t \\ 35 & \quad PQ^5 \cos p_1 t \cos^5 q_1 t \end{aligned} \quad (1)$$

The frequency determining quantities in these forms are each in the form $\cos p_1 t \cos q_1 t$ or this quantity times 40 one or more cosine squared quantities. Since $\cos^2 \alpha = \frac{1}{2} + \frac{1}{2} \cos 2\alpha$ the development of these quantities each contains one term of the form of $\frac{1}{2} \cos 2p_1 t \cos 2q_1 t$. This demonstrates that the terms of (1) each yields a 45 pair of second order side bands. These side bands for the several terms are superposed to comprise resultant side bands.

The amplitude of each of the resultant upper and lower side bands may accordingly 50 be expressed as a series the terms of which are proportional to $PQ, P^3 Q, P^5 Q, PQ^3, P^8 Q^3$ —all being products of even order.

These terms will be multiplied by the coefficients $b, d, f, \dots$ of the general equation. 55 In general these coefficients decrease in magnitude as the power of the terms of the general equation increases, that is, as the order of the above products increases. In fact the characteristic curve may be caused to 60 be substantially "square" so that substantially only the term PQ , which is linear in Q , is present. For other cases the other terms will be present in relatively small amounts and will introduce some distortion 65 on account of nonlinearity of certain of the

coefficients in Q . However, a number of the terms as $PQ, P^3 Q, P^5 Q, \dots$, hence their sum, will be linear in Q . The magnitude of the distorting terms, that is, $PQ^3, PQ^5, P^8 Q^3, \dots$, may be minimized by making P large as 70 compared with Q , so that substantial linearity may be obtained, as is necessary for distortionless transmission. This is true even though the characteristic curve departs widely from its "square" configuration. 75

It may be shown, in a manner similar to the above, that other side bands of a different even order may be obtained from other terms than those indicated in (1), in the expansion of the even power terms of the general equation. However, as will be more evident later, only those of the form $mp \pm q$ will have 80 coefficients which are linear in Q and, therefore, useful.

From the odd power terms of the general 85 equation odd order side bands may be similarly obtained. This will be demonstrated for the case of third order side bands.

From the expansion of these odd power terms (except the linear term) it will be 90 found that alternate terms, beginning with the second, have even powers of $\cos p_1 t$ and odd powers of $\cos q_1 t$. These terms in their regular order, up to and including those for the seventh power term of the general equation, are as follows, retaining, as in (1), only 95 the necessary coefficients:

$$\begin{aligned} & P^2 Q \cos^2 p_1 t \cos q_1 t \\ & P^4 Q \cos^4 p_1 t \cos q_1 t \\ & P^2 Q^3 \cos^2 p_1 t \cos^3 q_1 t \\ & P^6 Q \cos^6 p_1 t \cos q_1 t \\ & P^4 Q^3 \cos^4 p_1 t \cos^3 q_1 t \\ & P^2 Q^5 \cos^2 p_1 t \cos^5 q_1 t \end{aligned} \quad (2)$$

The frequency determining quantities in these terms are each of the form $\cos^2 p_1 t \cos q_1 t$ or this quantity times one or more cosine squared quantities.

Since $\cos^2 \alpha = \frac{1}{2} + \frac{1}{2} \cos 2\alpha$, the development of the expression $\cos^2 p_1 t \cos q_1 t$ contains the term $\frac{1}{2} \cos 2p_1 t \cos 2q_1 t$. The product of this term with the development of the remaining cosine squared quantities results in a term made up of the product of this term and $\frac{1}{2}$. Accordingly, the development of each of the terms in (2) contains a term of the form $\cos 2p_1 t \cos q_1 t$. This form is similar to the form $\cos p_1 t \cos q_1 t$ and in an analogous manner yields upper 110 and lower side bands of $2p$. This demonstrates that the terms in (2) each denotes a third order side band of the type $2p \pm q$.

The amplitudes of each of the resultant upper and lower side bands may accordingly 115 be expressed as a series, the terms of which are proportional to $P^2 Q, P^4 Q, P^6 Q, P^2 Q^3, P^4 Q^3, P^2 Q^5$. The sum of these terms is linear under the conditions discussed above for second order modulation. 120 125

That is, when there is only the third power term in the general equation, only the first term of the series occurs and the side bands are strictly linear in Q , and when there are 5 additional terms, there is a slight distortion which can be greatly minimized by properly proportioning the values of P and Q .

It may be shown in a similar manner that 10 third order side bands of the type $p \pm 2q$ may be obtained from other terms than those indicated under (2), of the development of the odd power terms of the general equation. The quantities expressing the amplitude of these side bands is made up of 15 terms none of which are linear in Q , so that the sum is not linear and cannot be made linear in Q . This means that third order modulation of this type cannot yield a faithful reproduction of the signal. The same 20 thing is true of other higher orders of modulation, even or odd, in which n is greater than one. These side bands may, however, be used in signaling where accurate reproduction of the modulating wave is not 25 essential.

Side bands of a higher odd order than third of the type $mp \pm q$ can also be obtained from the odd power terms of the general equation. These side bands, as well as 30 the higher even order side bands of the same type, can be made substantially linear in Q .

Although telephone systems now in use depend upon second order modulation and demodulation, experience has shown that 35 certain higher orders, especially the third, are substantially as suitable for the production of side bands and for the reproduction of speech. As illustrating the practicability of using the higher orders of modulation 40 it was recently found that in an actual carrier current telephone system arranged for optimum second order modulation conditions and for transmission of the unmodulated carrier component, the amplitude of 45 the third order side bands could, by adjustments not affecting the conditions of second order modulation, be made twice as great as that of the second.

It is apparent that the term "carrier frequency" must be re-defined for use in describing systems of modulation of higher order than the second. For example, a third order side band having frequencies $2p \pm q$, 50 can be demodulated to reproduce a signal by either second or third order demodulation, 55 depending upon whether a current of frequency $2p$ or p is available. Accordingly, depending on the order of demodulation, either of these two frequencies may play the 60 rôle played by the carrier frequency in a system using second order modulation (and accordingly second order demodulation). In this specification the terms "carrier current" and "carrier wave" will be applied to any 65 current or wave that may be combined in a

distorting device with the transmitted side band or side bands to produce a signal, and the frequency of such current or wave will accordingly be designated a carrier frequency. A modulated wave of a high order 70 may accordingly have as carrier frequencies both the frequencies of the impressed high frequency wave and certain of its harmonics. The impressed high frequency wave will be designated as the "impressed" "original" or "unmodulated" carrier wave. 75

Conditions favorable to the production of second order side bands are not necessarily favorable to the production of third order side bands or, generally, the conditions favorable to even order modulations are not necessarily favorable to odd order modulation, and vice versa. This is illustrated by Fig. 1 in which A and B are, respectively, the $E_c - I_b$ characteristic curve and the curve 80 of the second order side band output current of a modulator recently tested. The modulator circuit was of the general type illustrated in U. S. patent to Van der Bijl, No. 1,350,752, issued August 24, 1920. A tungsten filament carrying a current of 1.35 amperes was used. The plate potential was 220 85 volts. The important thing to notice about this figure is that when the grid is given a polarizing potential of -18 volts, the second order side band becomes substantially zero. This value of grid potential marks a point 90 of symmetry of the characteristic curve.

This condition, which is unusual and difficult to obtain with oxide coated filaments, 95 was made possible by reason of the choice of filament material and the critical values of the constants used. The other even order side bands would also be found to be substantially zero if modulation occurred 100 about the same point. Although the odd order side band output is not shown in the curve, it is not a minimum at that point.

The experiment demonstrates that if a 105 characteristic curve having symmetry about a point is represented by a power series, this series will have no even power terms, that is, the coefficients $b, d, f, \dots$, of the general equation will each have zero values.

Although it is not necessary, in order to 110 produce odd order side bands, to operate about a point of symmetry, such method of operation makes possible odd order modulation with suppression of even harmonics of the impressed carrier frequency and with 115 suppression of even order side bands since these components result from the terms in the general equation having the same exponents as the numbers indicating the frequency multiple. This expedient is of value, 120 in its economy of energy, in the avoidance of interference due to the presence at the receiver of even order side bands, and on account of its secrecy. Such a system is 125 relatively secret, since it insures that a 130

would be interceptor cannot detect the signal by second order demodulation between the odd order side bands and the appropriate even multiple frequency carrier. In multiplex communication systems using side bands of different orders for the respective channels (an example of which is illustrated in Fig. 15 and which will be described later) the expedient insures a greater separation between message carrying side bands.

Economy and secrecy are promoted in odd order modulation by complete carrier suppression, that is, by suppressing the impressed carrier as well as its even harmonics. This may be accomplished, for example, by suppressing the even harmonics as above, and suppressing the impressed carrier by means of a filter. Since the odd order side bands are far removed from the impressed carrier, separation can easily be effected by the filter. Suppression of the carrier frequencies may be accomplished in this simple manner without resort to balanced arrangements of tubes. This is of importance in instances where, if the usual second order modulating methods were to be used with carrier suppression, the carrier frequency would be too high to permit separation from the second order side bands without resort to such balanced arrangements.

Where it is difficult to provide a single tube having the requisite symmetry of characteristic to produce, exclusively, odd order side bands, a push-pull arrangement of modulator tubes may be used to produce such an effect. Fig. 2 illustrates such an arrangement. In this figure, p and q indicate, respectively, the sources of the corresponding impressed carrier and modulating currents. If the tubes have identical characteristics, if coils 1 and 2 are wound in the same direction, and if coils 3 and 4 are wound in relatively opposite directions, as indicated, this arrangement of tubes will produce odd order side bands and will suppress the modulated even order side bands and odd carrier frequency harmonics. Filter F may be used to suppress the impressed carrier and its even harmonics up to that harmonic which corresponds to the particular order of modulation used. For example, if only third order side bands were to be used the filter would be designed to suppress only the second harmonic of the impressed carrier, if fifth order side bands were to be used the filter would suppress the second and fourth harmonics. Either of these conditions would effectively correspond to complete carrier suppression. This arrangement of circuit, as well as other balanced circuit arrangements to be described below, is quite similar to certain forms of push-pull modulators discussed in U. S. patent to Carson No. 1,343,306, issued June 15, 1920, which also contains a general

analysis of the operation of push-pull modulators.

Alternatively, the two sources could be interchanged. This arrangement would not produce higher order side bands in the sense that this expression is used in this specification, that is, of the form $mp \pm q$. The arrangement therefore would not be useful in higher order modulation.

By reversing either coil 3 or coil 4 in the arrangement of Fig. 2, even order side bands may similarly be produced.

Fig. 3 illustrates a system of modulation or demodulation in which, depending on the adjustment of the quantities concerned, pronounced even or odd order side bands may be obtained.

Assuming for the present that the switch which short circuits the transformer 6, is closed so that this transformer is ineffective, circuit 5 is connected on one hand to the source of currents to be modulated or demodulated and on the other hand through transformer 6 to devices 7 and 8. The former may be any type of electric discharge modulator, the latter a rectifier for example, a two-electrode electric discharge device. Reference numeral 9 indicates a grid leak impedance for preventing too great an accumulation of negative charge on the grid of tube 7. This impedance (a resistance in the case illustrated) is preferably high, for example of the order of a megohm. The output current from the combination may be used as required in circuit 10.

The theory of the operation of the circuit is best explained with reference to Figs. 4, 5 and 6. Curve abc of Fig. 5 is characteristic curve of tube 7 plotted between grid-filament potential and plate-filament current. If the rectifier tube were not present so that the potentials would be impressed directly between the grid and filament of tube 7, the variations of impressed potentials would occur over the portion bc of the curve in the usual way and, since this portion of the curve exhibits only slight variations of impedance, the form of the plate-filament current would be a substantial reproduction of the form of the impressed potentials.

With the rectifier in circuit, the characteristic curve is modified, so as to assume the form bd, over the operating range. The plate-filament current, plotted on a time axis will be as indicated in Fig. 4, if a sine wave of impressed potentials is assumed. In this figure, the time periods represented by intervals between 1, 2, 3, 4, etc., are equal. If the non-horizontal portion of the characteristic curve were straight, the non-horizontal portion of the curve of Fig. 4 would have a sine wave configuration. With the characteristic disclosed, this portion of the curve

of fig. 4 is somewhat less pointed than a sine wave curve. According to the criterion established above, the modification of the normal characteristic is favorable to the production of even order side bands. This modification of the normal characteristic is easily explained when it is considered that the rectifier is an impedance element whose impedance varies by a very large factor, one hundred in a known instance, when the polarity of the potentials impressed are reversed. When positive half waves are impressed on the combination of tubes, that is, when the grid of tube 7 is positive with respect to the anode-element of tube 8, a grid-filament current tends to flow in tube 7 since its grid is positive relative to its filament. The impedance of the input circuit will correspondingly decrease. The total potential will divide according to the respective impedances of this input circuit and of the rectifier. The result will be that substantially all of the applied potential is impressed in effect across the rectifier. The potential impressed across the input of the tube 7 will correspondingly be very small or zero and the plate-filament current will uniformly, throughout the half cycle, have the value corresponding to zero grid potential.

When negative half waves are impressed on the combination of tubes, the conditions are the converse. The rectifier will have substantially zero impedance, the input circuit will have substantially infinite impedance, and the potentials will divide accordingly. This condition corresponds to the normal condition of operation of modulator tubes with negative grid potential and the operation will therefore occur over the normal portion *b* of the characteristic.

If the variations of potentials are sufficient to cause operation beyond the foot of the characteristic curve so that the modified characteristic assumes the form *e a b d*, the conditions are favorable to the production of odd order side bands. Fig. 6 indicates the corresponding plate-filament current curve plotted to a time basis. In this curve time periods indicated by intervals between points 1, 2, 3, 4, etc., are equal, as in Fig. 4.

It is apparent that the modified characteristic would be changed if the maximum amplitude of the impressed potentials were changed, since this would result in the operation over a greater or less extent of the horizontal portions of curve *e a b d* or, otherwise stated, it would result in the inclined portion of the characteristic curve becoming relatively greater or smaller. The corresponding effect on the current-time curve would be to change the slope of the sides of the curve. An increase in the maximum amplitude would cause the curve to approach a rectangular configuration. A rectangular configuration would be character-

ized by symmetry between consecutive half waves, since the time periods corresponding to the intervals between points 1_a , 2_a , 3_a , 4_a , etc., and 1, 2, 3, 4, etc., would all be equal. This limiting condition, which corresponds to an infinite maximum impressed potential, defines a situation in which there is an entire absence of even harmonics (if a modulating wave is superposed with the carrier wave on the modulator, an entire absence of even order side bands). The corresponding complete symmetry in the characteristic curve which should define this condition, is that which is attained when the inclined portion becomes relatively zero as compared with the infinitely extending horizontal portions. By using a moderately large amplitude of carrier potential, this limiting condition may be quite closely approximated.

A symmetry not dependent on the amplitudes of the impressed potentials, may be obtained by adding the other circuits of Fig. 3 shown between 5 and 10, as by opening the switch which short circuits transformer 6^a. There is no mutual inductance between the two sets of transformer windings 5, 6 and 6^a so that the opening or closing of the switch does not affect the operation of the transformer 6. The primary and secondary windings of transformer 6^a should be oppositely related as compared with the corresponding windings of transformer 6. This result may be accomplished by reversing the direction of winding of one of the coils of transformer 6^a with respect to the corresponding coil of transformer 6. The addition of the lower set of circuits will result in a current indicated by curve *e' a' b' d'* of Fig. 5 in the lower half of the primary of the output transformer during the time in which the current in the upper half is as indicated by curve *e a b d* of the same figure. The curve of resultant current in the primary, and accordingly the form of the current wave in the secondary, of the output transformer, with reference to the potentials applied to the combined primary windings of transformers 6 and 6^a, is the sum of these curves. In order to avoid unduly complicating the figure this curve is omitted. It is apparent, however, that it would be substantially straight about the origin and would have pronounced bends at the ends, if the operation extended that far, corresponding to the bends at the feet of the respective component curves. Fig. 6^a, which corresponds to Figs. 4 and 6 illustrates the current in the primary winding of the output transformer for this method of operation. Because of the higher degree of symmetry obtained and because it makes possible more effective utilization of the alternating current wave, the arrangement is sometimes preferred to that using a single modulating tube.

In the arrangement of Fig. 3, the two

windings of the primary of the output transformer are in aiding relation. If they are oppositely wound, even order modulation side bands may be produced to the exclusion of odd order side bands and odd power carrier harmonics.

A result similar to that obtainable by one pair of the sets of tubes of Fig. 3 can be obtained by substituting for the rectifier of Fig. 3, a resistance in the grid lead of a single three-electrode tube, such as resistance 11 of Fig. 7. If the potential variations across the secondary of transformer 6 (Fig. 7) causes the potential of the grid to tend to become positive, the potential drop in resistance 11 will modify this portion of the characteristic curve so as to cause an abrupt bend like that between *b* and *d* of Fig. 5.

Although electric discharge devices have so far been considered the number of kinds of devices that may be used for higher order modulation or demodulation is limited only by the number of those capable of modulation generally. The method in which modulation is effected by varying the inductance of a coil by correspondingly variably saturating its magnetic core, is especially applicable to suppressed carrier, odd order, modulation. Fig. 8 illustrates one modulating arrangement of this kind and also a system in which it, or any equivalent means, may be used.

In Fig. 8 numeral 12 indicates a modulator of this type which consists of a toroidal core wound with a single coil. The use of the condenser shown in dotted lines is alternative and will be referred to later when considering Fig. 12. The function of modulator 12 is to distort the currents flowing therethrough in the manner required to produce the desired side bands. Potentials of signal and carrier frequency sources 13 and 14, respectively, are impressed in common on the modulator through low pass and carrier filters FL and FC, which effectually prevent interaction between the two currents except as it occurs in the modulator. The amplitude of the impressed carrier may be adjusted for maximum amplitude of a particular desired side band by receiver shunt 15 or any other means having a like function. A receiver shunt of the type disclosed is described in U. S. patent to Blackwell, No. 1,261,096, issued April 2, 1918.

Modulator 12 suppresses even harmonics of the impressed carrier and even order side bands. The modulated wave is impressed by transformer 16 on filter FB which selects the side bands of the order desired or a single side band of that order. The transmitted currents are impressed on the transmitting conductor 18 through three-winding transformer 19. Device 17, which may be similar to 15, may be used if desired, to regulate the amplitude of the transmitted

side band. It may equally well be used at the receiving station. Circuit 18 may be a transmission line connecting two communicating stations or a pair of radio antennæ, one at the transmitting station and another at the receiving station.

Carrier current for demodulation is supplied through circuit 20, the switch 123 being closed, to points in the transformer 19 which are balanced with respect to the modulated wave input circuit. An artificial net-work 21 balances the line 18. The amount of carrier current energy required for the particular modulating and demodulating condition may be critically adjusted by device 22. The use of the three-winding transformer permits the independent transmission of as much carrier as may be desired without interaction with modulated side bands at the transmitting station.

The circuit elements DM, FL, and 23 at the distant stations serve to receive and utilize the wave impressed on conductor 18 and transmitted thereto. Assume, for the instant, that switches 125 and 126 are open.

With the particular arrangement so far described, since the carrier is transmitted, demodulator DM must be arranged for demodulation of the same order as the order of modulation used at the transmitting station. Any one of the specific types of modulators or demodulators described in this specification or their equivalents in function may be used.

The signal component is separated by low pass filter FL and impressed on telephones 23. The filters shown in several places in this and other figures of the drawing may be of any type capable of the functions indicated. U. S. patent to Campbell, No. 1,227,113, issued May 22, 1917, describes various types of filters from which selection may be made according to the particular transmission characteristic desired.

The operation of the magnetic core modulator of Fig. 8 will be explained by reference to Fig. 9. The curves *f* and *g* in this figure are the familiar B—H, or magnetization curves which express the relation between the magnetizing force H and magnetic induction B. Curve *f* is the magnetization curve for positive variations of H which would be obtained if a magnetic core, as, for example, the toroidal core in the magnetic modulator, having no initial residual magnetization, were variably magnetized by positive values of current. The curve *g* would be similarly obtained if negative values of magnetomotive force were used. Curves *f* and *g*, taken together, exhibit perfect symmetry about the origin. The permeability of the core is measured by the ratio of B and H, that is, by the slope of the chords of the magnetization curve between the origin and the reference points.

The curves which express the absolute values of permeability corresponding to curves *f* and *g* have approximately the shape respectively of curves *h* and *i*, which obviously must be symmetrical about the axis of ordinates. Since the permeability is a factor in the equation which expresses the inductance of the magnetizing winding, the inductance varies in accordance with these curves. If the variable saturation of the toroidal core with variable positive and negative values of impressed potentials, is assumed to follow these curves, the characteristic curve between the impressed potentials and current flowing through the coil would be obtained by dividing these positive and negative values by the ordinates of *h* and *i*. The resultant characteristic curve would correspond, for example, to the characteristic curve of Fig. 5, and would determine the modulating properties of the circuit. The curve would obviously have symmetry of the same type as that of curve *f* *g*, that is, it will have symmetry about a point. Accordingly, under the assumed conditions odd order modulation would be achieved with suppression of the even order side bands and of even power harmonics of the impressed carrier frequency. This result is achieved without the use of a polarizing means.

As a practical matter, the variation of *B* under conditions assumed above of variable *H* would, starting at the top of the positive magnetization curve, follow the familiar hysteresis loop *j*, *k*, *l*, *m*, in which the ascending and descending branches *m* and *k*, and correspondingly the branches *j* and *l*, are symmetrical with each other. Although the presence of residual magnetization affects the shape of the corresponding permeability curves, they are, as a matter of fact, of the same general form as *h* and *i*, and the symmetry of the loop insures that these permeability curves are symmetrical. Accordingly, the operation of the magnetic core modulator, even when there is hysteresis, has the desirable features of odd order modulation with suppression of the even order effects.

Of course, the hysteresis loop disclosed would result only if the magnetizing current has not more than one maximum and minimum per cycle, as for example, a sine wave current. In the actual case the magnetizing current consists of superposed carrier and modulating current, and the resulting wave form accordingly has numerous irregularities and reversals of slope. For this case the hysteresis loop disclosed illustrates, for example, only the uniformly recurrent loop corresponding to the carrier current. The irregularities due to the modulating current would properly be shown as both large and

small hysteresis loops having their origins in the loop disclosed.

It is desirable to use a core which saturates at a small value of magnetizing current so that the characteristic curve has pronounced bends at its two extremes, and accordingly so that there are more pronounced high order modulation effects. From another point of view, the use of a saturated core makes possible the production of high order effects with the small values of impressed potential, that for practical reasons, must often be used.

Although in the above the effect of variation of inductance has been described, the corresponding variation of effective resistance contributes, although usually to a smaller extent, to the result, so that the effect may be considered broadly as a variation of impedance.

In practice, it has been found that the use of an alloy metal known as "permalloy" for the core markedly improves the operation of the device. This metal is an alloy containing two elements of the magnetic group, such group being made up of manganese, iron, cobalt, nickel and copper. In its usual form the metal is an alloy of nickel and iron. Whatever its specific composition, it is distinguished by its pronounced magnetic properties and especially the remarkably low value of magnetomotive force required to produce saturation. These magnetic properties depend largely on the special heat treatment which is given to the alloy during its process of manufacture. A magnetic core modulator, made of a core wound with a ribbon of that material, the whole coil being approximately the size of a finger ring, was found to operate in the system of Fig. 8, with substantially the same efficiency and to give substantially as good reproduced speech as with the use of the conventional carrier current systems using vacuum tubes and second order modulation. Reference is made to a paper by Arnold and Elmen in the Journal of the Franklin Institute for May, 1923, for a detailed description of this alloy and its properties.

Although in Fig. 8 the potentials are shown impressed on the modulator in series, they may equally well be impressed in parallel, the particular arrangement of circuits depending upon the impedances of the filters outside the transmission bands, and therefore being determined by the laws governing the efficient connection of circuits generally. In general filters having low impedance outside the band should be connected in series. If the impedances outside the bands are high, they should be connected in parallel. A conductive instead of an inductive connection between the modulator circuit and filter FB may be used. Figs. 10 and 11 illustrate

arrangements in which conductive connections are used, and illustrate further the use of series and parallel connections of circuits. These figures illustrate the case of either modulation or demodulation and also the use of the same circuits for both modulation and demodulation. For this latter case, expediency may urge the use of separate coils for the two functions, one, the modulator, being designed for high signal wave amplitude and low signal wave frequency, and the other, the demodulator, being designed for low modulated wave amplitude and high impressed modulated wave frequency.

Instead of using a single modulator winding the arrangement of Fig. 12 may be used. Modulation is here effected by the varying self-inductance and resistance of the primary winding as in the arrangements above described, together with the varying mutual (varying leakage). Further, the capacitive secondary load, by reducing the demagnetizing effect of the secondary current, may be used to increase the flux density for a given magnetomotive force. The capacitive load further promotes the efficient operation of the modulator by reason of the selective characteristic of the secondary circuit when referred to the primary, if the secondary is tuned to resonance with the carrier frequency. The selective characteristic insures that there will be a relatively great variation of the inductance as the frequency is effectively varied by modulation around the resonant frequency. This effect is also present in the case of a modulator with a single winding. The condenser indicated in dotted lines in Fig. 8 illustrates an alternative arrangement of modulator 12 having this feature.

The modulating, carrier and side band currents, or certain of them, may even be caused to flow through separate coils on the core, as in Figs. 13 and 14.

The examples of magnetic coil modulators described above illustrate what might appropriately be denoted "longitudinal" magnetization, since the fluxes resulting from the two magnetomotive forces follow parallel, that is, the same paths. It has been found that a similar effect is produced by what may be called "cross" magnetization in which the windings are so arranged that the two fluxes tend to be normal to each other. The three circuits for the modulating, carrier, and side band currents may be otherwise related in either of the ways above described. The use of cross magnetization has an advantage, in a modulator or a demodulator, that mutual induction between the modulating and carrier circuits may be made substantially zero, therefore avoiding the necessity of the use of filters in these circuits. In a combined

modulator and demodulator, however, only the carrier filter may be omitted. The effect of cross magnetization on the permeability, as well as physical structures for accomplishing cross magnetization are described in an article by Goldschmidt in the Elektrotechnische Zeitschrift for March 3, 1910, page 218.

The arrangement of the system of Fig. 8 may be varied considerably from that shown. For example, the unmodulated carrier may be introduced at the receiving station, instead of being transmitted thereto from the transmitting station, by means of source 127, switch 125 being closed. The carrier may, of course, be transmitted from the transmitting station by an independent circuit. When it is not important to transmit modulated current of a particular frequency characteristic, filter FB may be eliminated or made with a sufficiently wide transmission band so that the carrier will be transmitted through transformer 16 to the transmitting conductor 18. If even order demodulation is used corresponding even harmonics of the unmodulated carrier may be similarly transmitted or locally introduced at the receiver. For example, the signal may be reproduced by second order demodulation if the double carrier $2p$ is used. The double carrier may be conveniently derived from source 14, as by the circuit described in U. S. patent to Kendall, No. 1,446,752, issued February 27, 1923, by opening switch 123, so that current from circuit 20 is supplied from source 14 through harmonic generator GH. It may be derived from double carrier frequency source 124 at the receiver, switch 126 being closed.

A substantial degree of secrecy may be obtained with the system of Fig. 8 by producing a lower third order side band, or a side band having similar frequency characteristics, suppressing the double carrier frequency, and transmitting the side band and the original carrier frequency, which should equal approximately the upper frequency of speech. Demodulation by the ordinary method, that is, second order demodulation, will give an audible frequency component represented by $(2p-q)-p$, which is substantially inverted speech. Any signal obtained by incidental third order of modulation will be effectually masked by this inverted speech. Only by using a demodulator which gives no second order side band as for example, by using the magnetic demodulator of the type shown in Fig. 8, may undistorted speech be obtained. The same principle may be applied if other orders of modulation and demodulation are used.

Multiplex signaling may be achieved with the system of Fig. 15 by using different orders of modulation, or at least using

methods of modulation producing side bands differing in frequency in a similar manner, for the different channels. Since the elements are each old or have been disclosed in other figures, and the general arrangement and relation of the channels, except for the specific features of the present invention, may be similar to that of conventional multiplex carrier current systems, the system is illustrated diagrammatically. Reference numerals 24 and 25 indicate two transmitting circuits of a multiplex carrier system. The corresponding receiving circuits are indicated by 26 and 27 and 28 indicates the line circuit. Low frequency signals from lines 29 and 30 modulate carrier current derived from source 31 in modulators M_1 and M_2 . The former produces second, the latter third, order side bands or side bands of similar frequency characteristics if produced by other methods which are selectively transmitted by filters F_1 and F_2 .

The transmitted side bands are selectively received by filters RF_1 and RF_2 and demodulated by demodulators DM_1 and DM_2 , the former being of the second, the latter of the third order type or of other types producing similar demodulation products. If the unmodulated carrier is transmitted, it may be utilized in the usual manner in the respective demodulators. It, however, may be supplied to both demodulators, or to either, by separate local source 31, or amplified carrier from demodulator DM_1 may be supplied to demodulator DM_2 , through filter F_2 . Demodulator DM_2 may, if desired, be of the second order type and be supplied with double frequency carrier through filter F_2 . Of course, other orders of demodulation may be used for the two channels disclosed. Additional channels using additional orders may be used. In particular, even order modulation (odd harmonic carriers) may be used for all the channels. If the harmonic frequency carriers are transmitted second order demodulation may be used, which provides a simple means for deriving from a single carrier source the various frequencies used in conventional multiplex harmonic systems. Since the carrier frequencies are odd multiples of the basic carrier frequency they cannot produce interfering effects by interaction, as would occur if even multiples were used.

The result achieved is similar to that of a multiplex harmonic system employing the usual second order modulation. However, besides the advantages which inhere in high order modulation as pointed out above, the system as a whole is characterized by a simplicity which is not found in other harmonic systems, especially on account of the avoidance of the use of harmonic generators.

Fig. 16 illustrates the use of a similar principle in a two-way signaling system in which the frequencies for the two directions

are fixed by a single source. The two one-way channels may be joined to a single line in each station by a conjugate connection as shown. The channel identified by M_1 , TF_1 , 28, RF_1 , DM_1 may be identical with the correspondingly labeled channel in Fig. 15. Similarly channel M_2 , TF_2 , 28, RF_2 and DM_2 may be identical with the other channel of Fig. 15, except that transmission occurs in the opposite direction. Source 31 supplies the current for the first channel and demodulated carrier for demodulator DM_2 may be selected by filter F_2 and supplied to the second channel. Obviously the two-way channel of Fig. 16 may be duplicated to constitute a multiplex signaling system having all of the features of the system of Fig. 15.

Although, of the higher orders, the application of odd order modulation has been emphasized as compared with even order modulation, this is only because the range of odd orders of modulation includes the lowest of these even higher orders. The amplitude of the side band of the several orders in general varies inversely as the order, as has been explained. This means practically that in general, third order modulation is to be preferred. A second reason for the emphasis on odd order modulation is that this type of modulation can conveniently be accomplished to the exclusion of even order modulation, a result frequently desired. The converse result, that is, even order modulation to the exclusion of odd order modulation, is not readily accomplished.

It is realized in view of the similar physical operation involved in modulation and demodulation, that there should be a single word to include both or either of these operations. Accordingly, in the claims the word "modulation" will be understood, where applicable, to cover both modulation and demodulation as ordinarily used.

It is also realized that side bands of identically the same frequency values as the high order side bands produced by the method described in this specification may be produced by other means, as by building up such side bands by a plurality of steps of second order modulation involving either reflex operation of a single modulating device or successive steps performed in different modulating devices. For example, side bands of frequencies $2p+q$ may be produced by doubling the carrier frequency in one step of second order modulation and then separately combining the wave of this double carrier frequency with the wave of frequencies q in the same or another device by another step of second order modulation. This process is old in the prior art and differs fundamentally from this invention as hereinbefore described. Consequently, it is

not desired to claim herein as new per se the process of or means for producing side bands of the form " $mp \pm nq$," $m+n$ being greater than 2, where their production involves successive separate steps of modulation or distortion in the same or different devices; although the inventive idea illustrated in Figs. 15 and 16 includes the production of side bands by both of these two methods and by other methods capable of producing side bands of similar frequency characteristics. Such side bands, however produced, are alike in their fixed frequency mp .

15 Since a high order modulated wave may be combined with either the original carrier or any multiple thereof, depending on the order of demodulation used, a word is similarly required to express these concepts. 20 Consequently, the word "multiple" will be used in the claims in a generic sense to include the single as well as plural multiples unless such an interpretation would be inconsistent with the context.

25 What is claimed is:

1. The method which comprises jointly impressing a carrier wave and a signal wave on the same distorting medium, and utilizing one or more of the resultant side bands of 30 higher than the second order.

2. The method which comprises jointly impressing a carrier wave and a signal wave on the same distorting medium, and utilizing resultant modulated components corresponding 35 to at least one order of modulation higher than the second.

3. The method, using a distorting device 40 which has an input-potential-output-current characteristic, the general equation of which includes odd power terms, which consists in jointly impressing waves of different frequencies on said device and utilizing the resultant combination frequencies of higher order than the second resulting from said 45 odd order terms.

4. The method using a distorting device, which consists in jointly impressing waves of different frequencies on said device, combining said frequencies in a single step to 50 produce side-bands of higher order than the second, and leading off from said device and usefully employing currents of said side-band frequencies.

5. The method of signaling which 55 comprises jointly impressing a carrier wave and a signal wave on the same distorting medium, transmitting the resultant modulated components having higher order than second, and demodulating said components to reproduce the signal.

6. The method of signaling which 60 comprises jointly impressing a carrier wave and a signal wave on a distorting device, transmitting at least one side band corresponding to at least one order of modulation higher

than the second, and combining said side band with a wave whose frequency is a multiple of the unmodulated carrier frequency in a distorting device, to reproduce the signal.

7. In a system including a single distorting device the method of signaling which comprises generating by higher order modulation and transmitting a modulated wave having the frequencies $mp \pm nq$, in which m and n are integers, at least one of which has a value greater than unity, p is the unmodulated carrier frequency, and q is the modulating frequency.

8. The method of signaling which comprises generating by higher order modulation a modulated wave having frequencies $mp \pm q$ in which m is an integer having a value greater than one, and p and q are respectively the unmodulated carrier and 85 modulating frequencies, transmitting said wave, and combining it at the receiver with a wave having a frequency which is a submultiple of m to reproduce the modulating wave.

9. In a system including a single distorting device the method of signaling which comprises generating by higher order modulation and transmitting a modulated wave having the frequencies $2p \pm q$, in which p and q are respectively the unmodulated carrier and modulating frequencies.

10. The method of signaling which comprises generating a modulated wave of the third order, transmitting said wave, and modulating it at the receiver with a carrier current to reproduce the modulating current.

11. The method of signaling which comprises generating modulated side bands of the third order, transmitting said side bands, transmitting a wave of the original carrier frequency, intermodulating said transmitted side bands and carrier wave in such a manner as to produce third order side bands, and indicating the third order side band which corresponds to the modulating wave.

12. The method of signaling which comprises generating modulated side bands of the third order, transmitting said side bands, intermodulating at the receiver said side bands and a wave of the original carrier frequency in such manner as to produce third order side bands, and indicating the third order side band which corresponds to the modulating wave.

13. The method of signaling which comprises generating modulated side bands of the third order, transmitting said side bands, intermodulating at the receiver said transmitted side bands with a wave having double the original carrier frequency in such a manner as to produce second order modulated side bands, and indicating the second order side band which corresponds to the modulating wave.

14. The method of signaling which comprises generating and transmitting a modulated wave having only the frequencies $mp \pm q$, in which p and q are respectively 5 the carrier and modulating frequencies and m is an integer greater than one, and reproducing the modulated wave at the receiver by combining said transmitted wave with a carrier wave.
15. The method of signaling which comprises generating a carrier wave, generating a modulating wave, producing odd order modulated side bands of said carrier wave, and at the same time suppressing the even 15 order side bands and even power carrier terms, suppressing the unmodulated carrier and transmitting the resultant waves.
16. A secrecy carrier signaling method which consists in generating and transmitting a wave having only the frequencies $2p - q$ and p , in which q is the frequency of the modulating current and p is the unmodulated carrier frequency, which is so chosen that $p - q$ is within the audible range, producing third order modulated side bands 25 from the received currents of said frequencies, and indicating that side band which corresponds to the modulating current.
17. A multiplex harmonic carrier transmission system comprising, means for generating a carrier wave, a single modulating device individual to each channel for modulating a portion of said carrier wave with one of a plurality of signal waves to produce, with all of said devices, a plurality of sets of side band waves of the type $mp \pm q$ 30 in which m is different for each such set of side band waves, means for transmitting said side band waves, and means at the receiver for combining said side band waves with a multiple frequency carrier current to reproduce the respective signal currents.
18. A multiplex harmonic carrier transmission system comprising means for generating a carrier wave, a single modulating device individual to each channel for modulating a portion of said carrier wave with one of a plurality of signal waves to produce, with all of said devices, a plurality 45 of sets of side band waves of the type $mp \pm q$ in which m is different for each such set of side band waves; means for transmitting said side band waves together with a carrier wave whose frequency is a multiple of the 50 original carrier frequency, including such frequency; means at the receiver for modulating one of said sets of side band waves with said multiple frequency waves to reproduce one signal wave; means for selecting a portion of the amplified multiple frequency wave from the modulated output of 55 said modulating means, and means for reproducing other signal waves by modulating the other side band waves with said selected multiple frequency carrier wave.
19. A two-way carrier wave signaling system comprising two stations, carrier wave generating means at one station, signal wave generating means at the same station, means for modulating a portion of the carrier wave with the signal wave, means for transmitting at least one of the modulated side bands with some of the unmodulated carrier to the other station, means for modulating said side bands with the unmodulated carrier at the other station to reproduce the signal, means for selecting a portion of the amplified carrier resulting from demodulation at the other station, a single modulating means for intermodulating said selected carrier and a signal wave at the other station to produce side bands having a fixed frequency which is a multiple, greater than one, of the fixed frequency of the wave received at the other station, transmitting at least one of the last mentioned side bands to the first station, and means for modulating the side bands received at the first station with a portion of said generated carrier wave.
20. A signaling system comprising a plurality of one-way channels for different transmissions and means whereby each channel employs an order of modulation different from the others.
21. A signaling system comprising two one-way channels for different transmissions each employing a different order of modulation.
22. A duplex system in which the oppositely directed channels employ different orders of modulation.
23. A signaling system comprising, a plurality of one-way channels, a carrier wave source, and a single modulating means individual to each channel adapted to utilize the waves from said source to produce side bands which have a fixed frequency which is different from the corresponding fixed frequency of the side bands in the other channels and a multiple of the frequency of said carrier wave including said carrier wave.
24. A signaling system comprising two one-way channels and a carrier wave source, each of said channels comprising a single modulating device for intermodulating said carrier waves with signal waves to produce side bands the fixed frequency of which is different from that of the corresponding side bands in the other channel and a multiple of said carrier frequency, including the frequency of the carrier.
25. The method of modulation which comprises impressing the modulating and carrier waves upon a distorting medium, and controlling the medium to have a sharply curved input-voltage-output-current characteristic, whereby pronounced high order modulation side bands are produced.
26. The method of producing odd order

side bands by a distorting device which consists in impressing the carrier and modulating waves on a distorting device, the characteristic curve between the input and output quantities of which has a double curvature, and causing the input frequencies to operate over a section of the curve having said double curvature.

27. The method of producing odd order modulation side bands to the exclusion of even order modulation effects, using a distorting device, which consists in impressing the carrier and modulating waves on a distorting device whose operating characteristic has two pronounced bends in relatively opposite directions and which are symmetrical about a point in the curve, and operating uniformly over said bends in both directions from said point.

28. The method of producing odd order modulation side bands using a magnetic core which consists in variably saturating the magnetic core in accordance with impressed alternating carrier and modulating currents, and variably inducing alternating potentials in accordance with said variable saturation.

29. The method of producing odd order modulation side bands using a magnetic core, a magnetizing winding, and an inductor winding, which consists in varying the permeability of the core by and in accordance with modulating currents flowing in the magnetizing winding, through maximum values in the two directions, and thereby inducing corresponding variable E. M. F.'s in said inductor winding.

30. The method of magnetic core modulation using a magnetic core and a combined magnetizing and inductor winding which consists in varying the permeability of the core by and in accordance with carrier and modulating currents flowing through said winding, through maximum values in the two directions, and thereby correspondingly varying the impedance of said winding whereby odd order modulated side band currents are caused to flow in said winding.

31. A magnetic core modulator comprising in combination a toroidal magnetic core, a magnetizing coil therefor, means for caus-

ing carrier and modulating currents to flow in said coil, the values of said currents and the magnetic proportions of said core being such that the core is periodically substantially saturated for opposite directions of flux, and an inductor circuit wherein there is induced variable E. M. F.'s corresponding to the variable saturation of said core.

32. A magnetic core modulator comprising in combination a magnetic core, means whereby carrier and modulating currents produce a magnetic flux in said core, and means whereby said currents together periodically vary the permeability of said core to a maximum in either direction.

33. The magnetic core modulator specified in claim 32 in which the magnetic core material is such that it has relatively high permeability at low magnetizing forces as compared with iron.

34. The magnetic core modulator specified in claim 32 in which the core is of a magnetic material comprising two elements of the magnetic group.

35. The magnetic core modulator specified in claim 32 in which the core is of a magnetic material comprising nickel and another member of the magnetic group.

36. The magnetic core modulator specified in claim 32 in which the core is of a magnetic material comprising nickel and iron.

37. The magnetic core modulator specified in claim 32 in which the core is of a magnetic material comprising nickel and another element of the magnetic group, the nickel component predominating and the material having a permeability higher than that of iron at low magnetizing forces.

38. The magnetic core modulator specified in claim 32 in which the core is of a magnetic material comprising nickel and iron in which the nickel component predominates and having a permeability higher than that of iron at magnetizing forces of the order of a few tenths of a gauss.

In witness whereof, I hereunto subscribe my name this 26 day of December, A. D. 1923.

EUGENE PETERSON.
